SALES STIMULATING PANEL

John A. T. Ellison, Seattle, Wash.

Application September 6, 1949, Serial No. 114,253

2 Claims. (Cl. 340—325)

1

My invention relates to a sales stimulating device wherein groups of lights flash on and off periodically, and wherein several predetermined rows of said lights are lit intermittently at different intervals, and co-ordinated with the ringing of a bell, to indicate a winner.

The general object of my invention is to provide a simple and inexpensive sales stimulating device which can be used in conjunction with retail selling to stimulate trade by providing an eye-catching criterion whereby prizes are given to customers.

This and other objects will be readily apparent in the following detailed description of my invention.

The drawing is a diagrammatic view of the electrical hook-up of my invention.

In the practice of my invention a plurality of lights are mounted on a suitable panel and are preferably arranged in parallel spaced rows which I have designated by the prefix letters A, B, C, etc. and are aligned in columns to which I have assigned suffix numerals. I have shown five rows and three columns, for purposes of illustration only, as any number of lights is permissible. It is desirable that the lights be colored heterogeneously with each row a separate hue so as to give contrast and set forth an appearance more striking to the eye.

I provide a transformer 3 to step down the normal power supply to two different voltages which I show as 6 volts and 50 volts for purposes of differentiation and not limitation. The 50 v. circuit leads to a starting switch SSw and into what I term an actuator 13 which comprises a synchronous motor slowly rotating a brush arm 14. Placed in radial alignment from the pivot of the arm 14 are three normally open switches X-11, X-12, and X-13. In such a position these switches are closed once with each revolution of the brush arm 14.

The switch X-11 prevents the arm 14 from coming to rest in alignment with switches X-12 and X-13 when SSw is opened. When SSw is open and X-11 is closed by the arm 14, current can flow from lead 32 to lead 33 and the motor of the actuator 13 will continue to run until the arm 14 moves past the switches. Thus switches X-12 and X-13 can never remain closed for more than an instant so that subsequent relays and solenoids in the circuits controlled by these switches, to be hereinafter explained, will never be imperiled by an excessive current supply thereto.

Switch X-12 controls the current to a grounded solenoid 21 in the stepper unit 18 while switch X-13 controls the current to the solenoid 22 in the selector unit 20. I have chosen the terms "stepper" and "selector" arbitrarily to distinguish the two units. The solenoid 22 is grounded

2

through the lead to the plugging jack PJ and from there through a variable number of ground leads 39 to the stepper unit 18.

All the lights have a 6 volt lead 37 thereto and each has a ground lead 38 entering the stepper unit 18. These ground leads 38 have respective terminals mounted at uniform interstices near the periphery of a fixed wheel in the stepper unit 18, with the terminals for each column of lights being adjacent one another. There are as many conductive arms 25 as there are columns of lights, these arms being rotatably mounted at the center of the wheel so that the arms can contact the terminals of the leads 38. The arms 25 are driven by a ratchet unit the pawl of which is actuated by the solenoid 21. The teeth of the ratchet wheel correspond in number to the ground leads 38 so that the arms 25 rotate an angular distance corresponding to the spacing of the terminals of the leads 38, upon each current impulse to the solenoid 21, said solenoid being energized each time the switch 12 is closed by the rotating brush arm 14. The arms 25 are continuously grounded so that each time they contact terminals lights are grounded through the corresponding lead 38 and grounded arm 25.

The ground terminals of each column of lights are arranged in different order about the wheel and the arms 25 are evenly spaced apart so that lights in the same row are never grounded at the same time. Thus groups of lights are continually flashing on and off, one group at a time at an interval dependent upon the speed of the arm 14, each group having a light from each column but in different rows.

Each of the ground leads 39 has a terminal mounted on the stepper unit, these terminals being placed at evenly spaced intervals on the fixed wheel on a circumference thereof different from that of the terminals of the leads 38. A conductive grounded arm 26 is rotatably mounted with the arms 25 so that it can contact the terminals of the leads 39 periodically as it rotates upon intermittent actuation by the solenoid 21. Accordingly the circuit to the solenoid 22 will be grounded and hence the solenoid energized as many times per revolution of the arm 26 as there are ground leads 39 plugged into the plugging jack PJ.

The selector unit 20 has two axially spaced brush arms 23 and 24 rotatably mounted therein on concentric shafts so that the arms are moved at slight angular distances upon each electrical impulse to the solenoid 22. The arm 23 is geared to move much more slowly than the arm 24 and the drive for both arms is completed by a ratchet unit, the solenoid 22 being used to actuate the pawl of such unit. Three normally open switches X-14, X-15 and X-16 are mounted with their terminal contact points radially aligned between

the travel orbits of the arms. The brushes of the latter are so arranged that the brush arm 24 closes X-14 and X-15 and the brush arm 23 closes all three switches per revolution of the respective arms.

It is desired to have two of the rows of lights lit periodically, one at a time, at different intervals. I designate row B as the short interval row and row A as the long interval row. Normally open switches X-5, X-6, and X-7 are provided which, when closed, complete the 6 volt circuit to the lights in row B. For purposes of clarity, I will hereinafter term these switches short-interval switches. Distinguished therefrom, a set of normally open switches X-1, X-2, and X-3, which complete the circuits to row A, are denoted as long-interval switches.

The switch X-14 controls the current supply to the normally-open switch X-4 and also a normally-open switch X-8 which in turn completes the circuit 42 to the bell relay R3 to be hereafter explained. Switch X-15 completes the circuit to relay R2 through a normally closed switch Y-1. The circuit to relay R-1 is completed by switch X-16.

When relay R-2 is energized it closes switches X-5 through X-8. The energizing of relay R-1 closes switches X-1 through X-4 and opens switch Y-1. Relay R-3 when actuated closes the normally open bell switch X-9 to complete the circuit to the bell 27 and opens a normally closed switch Y-2 which opens the lead 43 and thus stops the motor of the actuator 13. As hereinbefore discussed this motor cannot stop if the arm 14 is aligned with the switches X-11, X-12 and X-13.

The function of switch Y-1 is to open the circuit to relay R-2 when relay R-1 is energized by the arm 21 closing switch X-16 as well as switches X-14 and X-15, so that row B cannot light with row A.

Hence whenever row A or B lights, the bell 27 rings, and the arm 14 stops rotating. To start the device again a normally open reset switch RSw is provided which when closed actuates solenoid 22 and thus causes the corresponding arm 23 or 24 to move from alignment with switches X-14 to X-16. The opening of these switches opens the circuit to relay R-3 which causes switch X-9 to open, stopping the bell 27, and causes the switch Y-2 to close so that the circuit to the actuator motor is completed and the arm 14 set to rotating again.

In using the system, and by way of example, the lights can be mounted adjacent a gasoline pump. When the attendant starts to pump gas he starts the actuator so that groups of lights flash on and off. If the purchaser is lucky one of the rows A or B will light up and the bell will ring. If row B lights up the purchaser can be given a prize of one denomination, value considered, and if row A lights he is given a more highly prized item. When the gas delivery is completed the actuator is stopped. The device can also be used in conjunction with a cash register, in which case the arm 14 would be set to move an interval each time a sale is rung up. It will be noted that the plugging jack permits the proprietor to have control over the frequency of the lighting of a row so that proprietors of goods with a small mark-up can set the device so that

there will be fewer winners than would be desirable for sellers of goods with a large mark-up.

The invention, the manner of its use, and the advantages to be attained therefrom are thought to be apparent from the foregoing detailed description of my now preferred illustrated embodiment. Minor changes may be resorted to without departing from the spirit of the invention, and it is my intention that the hereto annexed claims be given a scope fully commensurate with the broadest interpretation to which the employed language fairly admits.

What I claim, is:

1. A sales stimulating panel comprising a plurality of lights arranged in rows and columns, said lights being divided into groups having a light from each column in different rows, normally open circuits to said lights, electrically actuated stepper means for periodically completing the circuits to said groups, one group at a time in the same interstice, an electrically actuated bell and a normally open bell circuit thereto, and electrically actuated selector means for periodically completing the circuits to a plurality of said rows one row at a time and at different intervals all greater than said interstice and for completing said bell circuit simultaneously with each completion of the circuits to a row.

2. A sales stimulating device comprising a plurality of lights arranged in rows and columns, said lights being divided into groups having a light from each column in different rows, normally open circuits to said lights, electrically actuated stepper means and a normally open stepper circuit thereto, an electrically actuated selector means and a normally both open and ungrounded selector circuit thereto, an actuator means periodically completing the stepper and selector circuits, said stepper means periodically grounding said selector circuit and periodically completing the circuits to said groups, one group at a time in the same interstice, an electrically actuated bell and a normally open bell circuit thereto, said selector means periodically completing the circuits to a plurality of said rows, one row at a time and at different intervals all greater than said interstice, and also completing said bell circuit simultaneously with each completion of the circuits to a row and means whereby said actuator means is inactivated in a position wherein said stepper and selector circuits are open simultaneously with each completion of the circuits to a row so that the lights in the respective row will remain lit and the bell will continue ringing until said stepper and selector circuits are manually completed by a reset switch.

JOHN A. T. ELLISON.
